GLASSWORKING APPARATUS

Charles A. Schuck, Corning, N. Y., assignor to
Corning Glass Works, Corning, N. Y., a corpora-
tion of New York

Application March 14, 1945, Serial No. 582,745

7 Claims. (Cl. 49—5)

1

The present invention relates to a glass working apparatus and particularly to a novel drive arrangement for synchronously operating a plurality of separate glass working assemblies.

An object of the invention is a simple, compact efficient and dependable drive for a plurality of working units.

Another object is a glass working machine of large production capacity compared to the floor space it requires.

Other objects and features of the invention will become evident upon further perusal of the disclosure.

In the accompanying drawings:

Fig. 1 is a plan view, with certain parts broken away and certain parts in section, of a machine embodying the invention;

Fig. 1a is an enlarged fragmentary view, partly in section, of the feeding trough arrangement for the machine;

Fig. 2 is a sectional elevation with certain parts broken away, taken generally along line 2—2 of Fig. 1;

Fig. 2a is an enlarged sectional view taken on line 2a—2a of Fig. 2 illustrating structural details of a mold and associated pressing mechanism;

Fig. 2b is an enlarged fragmentary detail of a plunger turret lifting device of the machine;

Fig. 2c is an enlarged sectional view taken on line 2c—2c of Fig. 2;

Fig. 3 is a sectional plan view illustrating the table drive and locking arrangement for the machine;

Fig. 4 is an enlarged sectional view taken on line 4—4 of Fig. 3;

Fig. 5 is a sectional view taken on line 5—5 of Fig. 4;

Fig. 6 is a side elevation partly in section of a fragment of the machine showing the conveyor drive arrangement;

Fig. 7 is a piping diagram for the machine;

Fig. 7a is an enlarged sectional view of a control valve used on the machine;

Fig. 7b is an enlarged sectional view of a pilot or line valve used on the machine.

General description

The instant disclosure embodies the invention in a glass pressing assembly wherein three similar rotating table presses equipped with Geneva type driven elements or wheels 38¹—38³ (Fig. 3) are grouped in like relation about a central or main table drive shaft 16. A drive roller 42 supported

2

between arms 41 of a single drive unit 26 (Figs. 2, 3, 4 and 5) carried by shaft 16 is successively cooperative with drive channels 43¹—43³ of wheels 38¹—38³ of the respective presses to successively turn their mold tables 55¹—55³ (Fig. 7) about their supporting columns 22¹—22³ as required to index their molds 56¹—56³ at loading, pressing and unloading positions. The single drive unit 26 has associated therewith a locking cam 39 which locks two of the wheels 38¹—38³ against turning while the remaining wheel is being driven.

Each of the mold tables 55¹—55³ (Fig. 7) has a three plunger pressing turret like turret 85 of table 55³ (Figs. 1 and 2) cooperative with a single pressing ram, like ram 97³, Figs. 2 and 2a, associated with turret 85, turret 85 being so geared to the table that its pressing plungers are advanced in succession to a position under ram 97³ (Figs. 2 and 2a).

Molds 56¹—56³ of the respective tables 55¹—55³ (Fig. 7) are supplied in succession with glass charges sheared from a stream of glass from a forehearth outlet (not shown) aligned over a distributing member 81 (Figs. 1 and 2) carried at the top of the drive shaft 16 which successively brings member 81 into register with chutes leading to molds in the charging positions of the respective tables 55¹—55³.

The operation of the shears (not shown) is under control of a pilot valve 132 (Figs. 1, 2, and 7) actuated by a three-lobe cam 130 carried by shaft 16. Operation of pressing rams 97¹—97³ of the respective tables in proper sequence to effect lowering of the rams is by means of control valves 125¹—125³ (Figs. 1 and 7) under influence of pilot valves 127¹—127³ (Figs. 2 and 7) adapted to be operated in succession by a lobe 128 on the under side of the shear control cam 130. Valves 125¹—125³ are actuated to effect raising of the rams 97¹—97³ by means of a cam 126 having a single lobe 126' also carried by shaft 16. On the sides of the tables opposite those at which pressing is done (Figs. 1, 2 and 7) shove-up units 82¹—82³ (Figs. 1, 2 and 7) are provided to lift mold valves, such as valve 58 (Fig. 2a), to clear articles from the molds, whereupon blasts of air from nozzles 142¹—142³ (Fig. 7) deliver the articles through a delivery trough such as 124 (Fig. 1) onto a conveyor 115 (Fig. 1) surrounding all three table presses. Spray guns 1a, 2a, 3a (Fig. 7) are associated with the respective tables 55¹—55³ as required to direct lubricating and cooling sprays toward the respective plungers 95 thereof (Fig. 2a) soon following their use and guns 1b, 2b and 3b are provided for similarly treating the molds

56¹—56³ and their valves such as 58 while at their unloading positions.

The raising and lowering movements of the shove-up units 82¹—82³ are under the influence of control valves 135¹—135³ and their associated pilot valves 136¹—136³ and 139¹—139³ (Fig. 7), adapted to be actuated by cams 137¹—137³ of the respective tables 55¹—55³. The supplying of air for rendering the spray guns 1a, 2a, 3a, and 1b, 2b and 3b effective is through valves 141¹—141³ which are also adapted to be actuated by the table cams. The arrangement is such that operation of a shove-up unit of any table and of the associated spray guns is rendered effective during indexing movements of the remaining two tables.

The pilot valves 127¹—127³, 136¹—136³, 139¹—139³, and 141¹—141³ (Fig. 7) are identical in form and accordingly a description of valve 136¹ (Fig. 7b) will suffice. Valve 136¹ is of the ordinary poppet type comprising a housing 143 having inlet and outlet ports 148 and 149 with the passage therebetween normally closed by a valve element held on its seat by a spring 147 and adapted to be opened by engagement of its stem 146 with a cam or the like. Valves 127¹—127³ and valves 136¹—136³ and 139¹—139³ have their outlet ports open to atmosphere, whereas the outlet ports of valves 141¹—141³ serve as the air supply ports for spray guns 1a, 1b, 2a, 2b, 3a and 3b. The way in which valve 132 is employed depends, of course, on the type of shear control equipment associated therewith.

Valves 135¹—135³ are alike and of conventional form. Referring particularly to Fig. 7a, valve 135¹ comprises a cylinder 150 containing a piston 138 of the balanced type and having an air inlet port 151, pneumatic unit air supply ports 134 and 134', valve control ports 133 and 133', and the usual exhaust ports x. In this type of valve air is constantly supplied to port 151 and through miniature apertures 152 and 152' therein to the respective ends of cylinder 150 so that as long as the pilot valves connected to ports 133 and 133' remain closed, piston 138 remains in the position to which it has last moved. When this balance is temporarily destroyed by opening of a pilot valve associated with the opposite end of the control valve, the piston shifts to such opposite end of cylinder 150. The piston 138 in one position supplies operating air to one pneumatic unit via a passage therein, not shown, but in communication with passage 138³ and inlet port 151 and connects the other end of such unit to atmosphere via passages 134, 138² and one of the exhaust ports x. With the piston 138 in its alternative position, air is supplied through port 134 to the unit and is exhausted from the unit through port 134' and valve passage 138¹ and the remaining exhaust port x.

For a more thorough description of a valve such as 135¹, see Goodrich Patent 2,267,236, granted December 23, 1941. Valves 125¹—125³ differ from valves 135¹—135³ only in that a pilot valve similar to valve 136¹ is incorporated in one end of the same structure. In other words, a valve such as valves 125¹—125³, may be made by connecting port 133 or 133' of a valve, such as 135¹, direct to port 148 of a valve such as 136¹.

General structural and drive arrangement

The machine for convenience of portability comprises a wheeled carriage 11 (Fig. 2) having a bed 12 carrying a base 13 provided with a centrally disposed hub 14 containing a bearing 15 serving the lower end of table drive shaft 16.

Symmetrically arranged with respect to hub 14 are similar housings such as 21 (Fig. 2) for the three fixed columns 22¹—22³ (Figs. 1, 2 and 3) about which the wheels 38¹—38³ and their associated mold tables 55¹—55³ rotate. Shaft 16, just above its bearing 15, has keyed thereto the table driving and locking unit 26 which has bolted thereto a worm wheel 27 in mesh with a drive worm 28 carried by a main drive shaft 29 continuously driven by a motor 30 (Fig. 1). As will be evident from an inspection of Fig. 3, roller 42 of drive unit 26 is adapted to successively travel in channels 43¹—43³ of wheels 38¹—38³ to successively drive them in step-by-step fashion while the semi-circular locking tooth 39 (Figs. 3, 4, and 5) is adapted to mesh with two of the semi-circular locking channels 40¹—40³ of wheels 38¹—38³ surrounding the shaft 16 while the remaining wheel is being driven. This is accomplished by providing the locking tooth 39 with a surface which extends through 240° of the circle surrounding shaft 16 formed jointly by one each of channels 40¹—40³ so that one of the wheels 38¹—38³ is locked against rotation until the trailing end of tooth 39 has passed clear of the first encountered half of one of such locking channels. This is illustrated in Fig. 3 where it will be observed the drive roller 42 is shown entering a drive channel 43¹ of the wheel 38¹. It will be evident from the foregoing that wheels 38²—38³ are positively locked against rotation while the remaining wheel 38¹ is being turned and further, because of the shown relationship of the drive channels 43³ and 43¹ of the last driven wheel 38³ and the next wheel 38¹ to be driven, that unlocking of wheel 38¹ only occurs concurrent with its being placed under control of the drive roller 42.

Table assemblies

40 Each mold table is supported in accordance with the showing of table 55³ which is supported on a flange 52 of a sleeve 33 arranged about its column 22³ supported on a thrust bearing 23 (Fig. 2) resting on the column housing 21. Flanged sleeve 33 near its lower end carries a ring gear 34 in mesh with a spur gear 35 carried by the shaft 86 of the plunger turret 85. As will be understood, each time wheel 38³ is turned to index a different mold under ram 97³ it turns turret 85 as required to index a different plunger 95 (Fig. 2a) under ram 97³. The sleeve 33 also intermediate its ends has a flange 50 co-operative with a cover 51. Table 55³ is, in the present illustration, equipped with block molds 56³ although the structure may be readily modified to employ other types of molds. Each such mold is carried by an insert such as 57 (Figs. 2 and 2a) fitting into a suitable aperture in the table. If desired, other inserts may be substituted for insert 57 as required to accommodate different size molds or the inserts may be dispensed with entirely if a large enough mold is used. Each mold is equipped with a valve 58 having a stem 59 fitted into a pusher 60 (Fig. 2) projecting through the underside of the table and adapted to be lifted by the push-up unit at the unloading position.

Mold temperature control

As characteristic of each of the three table presses, a cavity 61 below each mold 56¹ (Fig. 2) is in communication with a bored out upper portion of the associated column 22¹ via a port 20 through the column wall which at its upper end is connected with a temperature controlling fluid supply pipe 17. A passage 62 is provided for each

mold cavity 61 and is adapted to be brought into alignment with the ports 20 so that in any indexed position of the table each passage 62 is in alignment with a port 20 entering a cavity 61. That of the ports 20 which is aligned adjacent a mold indexed at the loading position is blocked by a plug 64 (Figs. 2 and 2c) attached to the lower end of a rod 74 projected down into the bore of column 22¹. Manually operable dampers 75 are also provided in passages 62 to individually regulate the amount of fluid supplied to the molds in accordance with their indexed positions. The molds shown do not require forced cooling or heating and therefore are not vented although fluid supplied to them can pass through the space 58¹ surrounding the valve 58 and thus cool the molds to a limited extent.

Mold Charging

An upper bearing support 66 (Fig. 2) for shaft 16 bridges the columns 22¹—22³ and has suspended therefrom a funnel such as 67 for each mold table 55¹—55³. Each funnel 67 is attached to a carrier 68 vertically slideable on posts 69 and 80 secured at their upper ends to support 66. Each carrier 68 is provided with a roller 70 which rides over a cam track 71 carried by shaft 16. It will be understood therefore that the funnels such as 67 are raised and lowered in succession as shaft 16 is rotated, being lowered into close proximity to molds 56¹—56³ to assure the charges being properly guided into the molds. Mold charges enter the funnels such as 67 through troughs such as 76 (Figs. 1a and 2) passing through suitable apertures in support 66 and arranged in alignment with elbows such as 77 and the associated guide trough 77' arranged on a plate 79 carried by posts such as 80 threaded into support 66. As previously stated, molds 56¹—56³ are charged with gobs of glass sheared from a stream flowing from a forehearth (not shown) whose bottom outlet is aligned over the input end of the distributing trough 81 (Figs. 1 and 2) which delivers them into the respective guide troughs 77'. The shearing of charges is accomplished in any conventional manner under control of the shear pilot valve 132 and, as illustrated in Fig. 7, cam 130 has shear control lobes 131¹—131³ so that during a single revolution of shaft 16 not only is each table indexed as already described, but also three charges of glass are severed so that a mold of each table receives a charge.

Pressing

The previously mentioned plunger turret 85 (Figs. 1 and 2) and its tubular drive shaft 86 are carried by the drive rod 87 of a pneumatic unit 88³ mounted on a support 89 bridged between the nearby column 22³ and a conveyer supporting column 90. Air is continuously supplied to the lower end of unit 88³ to normally hold the turret 85 in the position in which it is shown. Each pressing plunger 95 (Figs. 1 and 2a) carried by turret 85 is surrounded by a mold ring assembly 96 suspended from turret 85 by bolts 91 slideable in apertures therethrough. Lowering of a plunger 95 in alignment with a mold 56³ and of the entire turret 85 is effected by the ram 97³ which comprises the lower end of drive rod 98 of pneumatic unit 99³ arranged on support 89, unit 99³ being powerful enough to overcome the upward pressure of unit 88³. Ram 97³ is surrounded by a flanged ring 101 adapted to engage bolts 91 as the ram is lowered and to move mold

ring 96 down under compression of a spring 102. The bottom end of ram 97³ is tapered at 94 to fit a tapered cavity 100 in plunger 95 to assist in proper alignment of the parts during operation. Also the taper 94 of ram 97³ is a guard against damage of the parts should the turret 85 be turned while the ram is still on a plunger 95. The air continuously applied to the unit 88³ of turret 85 raises it as soon as ram 97³ restores. Obviously, it is vital that the turret 85 be raised prior to an indexing movement, as otherwise movement of the mold 56³ in interfered with by association of a plunger 95 and mold ring 96 therewith. Accordingly, the pneumatic unit 88³ is not entirely depended upon for the raising of turret 85. In addition there is provided a shaft 105 (Figs. 1, 2, and 2b) having at one end an arm 106 (Fig. 2b) connected by a link 106' to a turret lifting arm 107 arranged under the lower end of a shaft 108 depending from turret drive gear 35. The other end of shaft 105 is provided with an arm 109 (Fig. 2) having on its free end a roller 110 adapted to travel on a crown cam 111 arranged to be rotated by shaft 16. The contour of cam 111 is such that upon the indexing movement of one table, the arm 109 of the table at which pressing last took place functions to turn its shaft 105 as required to cause its arm 107 to raise its turret 85 if for any reason its respective pneumatic unit 88¹—88³ has failed to previously perform such function.

The pneumatic units 99¹—99³ (Fig. 7) which, through the medium of their rams 97¹—97³ lower their pressing plungers such as 95, are supplied with operating air through their control valves 125¹—125³ which, as previously mentioned, shift to supply air to lower their rams 97¹—97³ under the influence of their pilot valves 127¹—127³ (Figs. 2 and 7) which are so positioned as to be actuated in succession by cam lobe 128 which is adjustably arranged as at 128' on the under side of cam 130. The single lobe 126' of cam 126 (Figs. 2 and 7) is provided for controlling the shifting of valves 125¹—125³ to a position to supply air to units 99¹—99³ to raise their rams 97¹—97³, cam 126 being carried by a flanged collar 129 adjustably clamped at 129' to table drive shaft 16.

Unloading

The mold valve shove-up units 82¹—82³ (Figs. 2 and 7) are moved up and down by air supplied to them through control valves 135¹—135³. Shifting of any valve 135¹—135³ to supply air to raise its associated shove-up unit 82¹—82³ is under control of the pilot valve 136¹—136³ of the next table to be indexed. For example, the shove-up control valve 135² associated with the table 55² (Fig. 7) is shifted to supply air to move its unit 82² up when the pilot valve 136³ of table 55³ is actuated. Actuation of the pilot valve 136³ is by means of table cams 137³. Shifting of any shove-up control valve 135¹—135³ to supply air to lower its associated shove-up unit 82¹—82³ is under control of the second following table to be indexed. By way of example (Fig. 7), the shifting of shove-up control valve 135² to supply air to move its unit 82² down occurs when the pilot valve 139¹ of the table 55¹ is actuated.

The conveyer 115 (Fig. 1) is driven by one of three sprocket wheels 116 coupled to a speed reduction unit 118 (Fig. 6) driven by a belt 119 extending between it and a pulley 120 on the end of the main drive shaft 29. Ware delivered to conveyer 115 may be removed therefrom in any

desired manner, for example, as by sweeping it onto a straight line conveyor.

Lubrication

For the purpose of lubricating and assisting in cooling the molds, valves and plungers, spray guns 1a, 2a, 3a, and 1b, 2b and 3b (Fig. 7) are associated with tables 55¹—55³ as necessary to direct sprays towards molds 56¹—56³ while in their unloading positions and towards the plungers such as 95 which have been last employed. As previously mentioned, application of air to the spray guns is through valves adapted to be actuated by cams of the respective tables. For example, the guns 2a and 2b, associated with the table 52², are under control of a valve 141¹ associated with the table 55¹. Spraying of a mold, valve and plunger at table 55² accordingly occurs while the table 55¹ is indexing.

Operation

As shown, the table 55³ located at position 3 (Fig. 7) has just been indexed and, for the purpose of describing the sequence of operations, those occurring during the next one-third revolution of the main drive shaft 16 required to index the table 55¹ at position 1 will now be described. During this movement the lobe 128 on the underside of cam 130 engages and actuates the pilot valve 127³ which is individual to the table 55³ which causes the associated control valve 125³ to shift and supply air to the upper end of unit 99³ causing ram 97³ of the table 55³ to be lowered to press a charge previously deposited in the mold thereunder; shear pilot valve 132 is operated by the lobe 131³ of cam 130 to effect the release of a charge of glass into the glass distributing member 81 which, in the newly adjusted position will deliver the charge into a mold of the table 55¹ just after the indexing movement has ceased; and the lobe 126' of cam 126 causes the control valve 125² to shift as required to supply air to its unit 99² to raise its ram 97².

The indexing of the table 55¹ brings a previously charged mold under its pressing plunger, while its cams 137¹ actuate the associated pilot valves 136¹, 139¹, and air supply valve 141¹. Pilot valve 136¹ causes control valve 135³ to shift and supply air to raise its shove-up unit 82³, whereupon the article which is raised clear of its mold by such operation is delivered to conveyor 115 by air issuing from the associated nozzle 142³, as already mentioned. Actuation of pilot valve 139¹ causes the control valve 135² to shift to lower its shove-up unit 82²; and air supply valve 141¹ upon actuation feeds air to spray guns 2a and 2b associated with table 55² to direct lubricant against plunger and mold units thereof.

During the second one-third revolution of shaft 16 the table 55² is indexed. During this movement the lobe 128 on the underside of cam 130 engages and actuates pilot valve 127¹, associated control valve 125¹ being caused to shift and supply air to the upper end of unit 99¹ causing ram 97¹ to be lowered to press the charge previously deposited in the mold thereunder; shear pilot valve 132 is operated to effect the release of a charge of glass into the glass distributing member 81 which, in the newly adjusted position will deliver the charge into a mold of the table 55² just after the indexing movement has ceased; and cam lobe 126' shifts control valve 125³ causing it to supply air to its unit 99³ to raise its ram 97³.

The indexing of table 55² brings a previously charged mold under its pressing plunger, while its

cams 137² actuate the associated pilot valves 136² and 139² and air supply valve 141². Pilot valve 136² causes control valve 135¹ of table 55¹ to shift and supply air to raise its shove-up unit 82¹, whereupon the article which is raised clear of its mold by such operation is delivered to conveyor 115 by air issuing from the associated nozzle 142¹ as already mentioned. Pilot valve 139² causes the control valve 135³ to shift to lower its shove-up unit 82³; and air supply valve 141² associated with the table at position 2 feeds air to spray guns 3a and 3b associated with the table 55³ to direct lubricant against plunger and mold units thereof.

As the revolution of shaft 16 is being completed, table 55³ is indexed. During this movement the lobe 128 on the underside of cam 130 engages and actuates that pilot valve 127² which is individual to table 55², which causes the associated control valve 125² to shift and supply air to the upper end of unit 99² causing ram 97² to be lowered to press the charge previously deposited in the mold thereunder; shear pilot valve 132 is operated to effect the release of a charge of glass into the glass distributing member 81 which, in the newly adjusted position, will deliver the charge into a mold of the table 55³ just after the indexing movement has ceased; and the lobe 126' of cam 126 shifts control valve 125¹ as required to supply air to its unit 99¹ to raise its ram 97¹. The indexing of the table 55³ brings a previously charged mold under its pressing plunger, while its cam 137³ actuates the associated pilot valves 136³, 139³, and air supply valve 141³. Pilot valve 136³ causes control valve 135² to shift and supply air to raise its shove-up unit 82², whereupon the article which is raised clear of its mold by such operation is delivered to conveyor 115 by air issuing from the associated nozzle 142², as will be clearly understood. Pilot valve 139³ causes the control valve 135¹ to shift to lower its shove-up unit 82¹; and air supply valve 141³ feeds air to spray guns 1a and 1b to direct lubricant against plunger and mold units thereof.

45

Adjustability

It is to be noted that with the glass charge distributing member 81 in the angular position shown with respect to the table drive roller 42 a mold of the table at position 1 is charged substantially at the same time that a previously charged mold on the same table is being pressed, so that the time provided for the charge to settle is relatively long. This, however, need not be the case, since by merely shifting the position of the distributing member 81 the charge can be deposited in a mold of the table at position 2 or 3 while a charge mold of the table at position 1 is being pressed. Further variation of the time lapse between charging and pressing can be effected by shifting the position of shear pilot valve 132. Also, whereas in the present disclosure the position of the lobe 128 is such that pressing at any table occurs substantially as soon as the table has been brought to a stop, by shifting the position of lobe 128 on cam 130 the time of pressing can be changed. Similarly, by shifting cam 126, the time at which its lobe 126' operates the control valves 125¹—125³ can be advanced or retarded to vary the period of dwell of a plunger within a mold. As will be observed (Fig. 1), valves 136¹—136³, 139²—139³, and 141¹—141³ actuated by table cams 137²—137³ may also be shifted to modify the timing of the operations under their control to establish best operating conditions.

Although in the foregoing there has been shown and described the preferred embodiment of the invention, it is to be understood that minor changes in the details of construction and combination of parts may be resorted to without departing from the spirit and scope of the invention as claimed.

I claim:

1. In a glass working machine, three table units arranged in a triangle, a driven wheel for each table unit arranged concentric thereto, an endless conveyer surrounding the table units, a driver for successively engaging the respective wheels to turn them in sequence, means for supplying charges of glass to the respective units in succession, and means whereby the respective units fabricate the charges received into ware and deliver it to said conveyer.

2. In a glass working machine, a group of three table units arranged in like relation to the axial center of the machine, a wheel for each unit arranged concentric thereto, a drive shaft passing through the axial center of the machine having associated means adapted to successively turn said wheels whereby each unit is indexed in turn, and means for positively locking two of the table units against turning movement while the remaining table unit is being turned.

3. In a glass working machine, a group of glass working units arranged in like relation to the axial center of the machine, drive wheels for said units, continuously rotatable driving means successively cooperative with said drive wheels to impart turning movements thereto about their own axial centers in succession, a drive shaft for said driving means, charge receiving means carried by said shaft, and equipment for guiding charges delivered to said receiving means to the respective units.

4. In a glass working machine, a group of glass working units each rotatable about its own axial center and each having a plurality of fabricating assemblies, a drive wheel for each unit arranged coaxial therewith, driving means rotatable about the axial center of the machine adapted to impart turning movements to said wheels in succession, a shaft supporting said driving means, charge receiving and distributing means actuated by said shaft to distribute charges in succession to the respective units, and means associated with each unit for guiding charges into the respective fabricating assemblies thereof.

5. In a glass working machine, three table units arranged in a triangle, a drive wheel associated with each table unit, a driver for successively engaging the respective drive wheels to turn them in sequence, drive means for said driver, means for supplying charges of glass to said units in succession, means associated with each unit operated under control of said drive means to fabricate received charges into finished ware, and

means for positively ejecting the finished ware from said units.

6. In a mechanical movement, three wheels each having six equally and alternately spaced driving and locking channels, said wheels being arranged in the same plane and with their axes parallel and positioned at the apices of an equilateral triangle, respectively, and being grouped substantially as near to the center of such equilateral triangle as their peripheries will permit, a single drive means pivoted about the center of such equilateral triangle for successively engaging the driving channels of said wheels to impart rotary movement thereto, and means associated with said drive means simultaneously cooperative with the locking channels of two of said wheels to lock them against rotation while the remaining wheel is being rotated, the arrangement of said wheels being such that the drive means engages 10 a driving channel of the next wheel to be rotated before it leaves a driving channel of the wheel being rotated.

7. In a mechanical movement, three wheels each having six equally spaced driving channels, 20 said wheels being arranged in the same plane with their axes parallel and positioned at the apices of an equilateral triangle, respectively, and being grouped substantially as near to the center of such equilateral triangle as their peripheries will permit, and driving means pivoted about the center of such equilateral triangle for successively engaging the driving channels of said wheels to impart rotary movement thereto, the arrangement of said wheels being such that the driving 30 means engages a driving channel of the next wheel to be rotated before it leaves a driving channel of the wheel being rotated.

CHARLES A. SCHUCK.
